UNITED STATES PATENT OFFICE.

HARRY S. VROOMAN, OF CHICAGO, ILLINOIS.

DESIGN FOR A FIRE-BRICK.

SPECIFICATION forming part of Design No. 29,842, dated December 20, 1898.

Application filed November 12, 1898. Serial No. 696,311. Term of patent 14 years.

To all whom it may concern:

Be it known that I, HARRY S. VROOMAN, a citizen of the United States, residing at Chicago, Cook county, Illinois, have invented and produced a new and original Design for a Fire-Brick, of which the following is a specification, reference being had to the accompanying drawings, forming a part thereof.

Figure 1 is a perspective view of a fire-brick, showing my new design. Fig. 2 is an end view of the same.

As shown in the drawings, my fire-brick is rhomboidal in general contour and is formed with its upper and lower edges a and a' parallel and with the cross diameter of the former slightly greater than the cross diameter of the latter. Extending outwardly and downwardly at an obtuse angle from the upper edge a is a side face b , the vertical diameter of which is approximately one-third of the vertical diameter of the brick. Extending outwardly and upwardly at an acute angle from the lower side a' is a side face b' , the ver-

tical diameter of which is approximately two-thirds of the vertical diameter of the brick. 25

On the side of the brick opposite the faces b and b' and extending at an acute angle inwardly and upwardly from the edge a' is a face c' , the vertical diameter of which is approximately two-thirds of the vertical diameter of the brick, and extending downwardly and inwardly from the edge a is a face c , the vertical diameter of which is one-third of the vertical diameter of the brick. The faces c and c' join at an obtuse angle. 30

Having thus described my invention, what I claim as new, and desire to secure by Letters Patent, is—

The design for a fire-brick substantially as shown and described. 35

In testimony whereof I affix my signature in presence of two witnesses.

HARRY S. VROOMAN.
